(57) **CLAIM**

The ornamental design for a container with cap, as shown and described.

DESCRIPTION

FIG. 1 is an isometric view of a top, front, and right side of an ornamental design for a container with cap;

FIG. 2 is a front elevational view of the container with cap of FIG. 1;

FIG. 3 is a rear elevational view of the container with cap of FIG. 1;

FIG. 4 is a right side elevational view of the container with cap of FIG. 1;

FIG. 5 is a left side elevational view of the container with cap of FIG. 1;

FIG. 6 is a top plan view of the container with cap of FIG. 1; and,

FIG. 7 is a bottom plan view of the container with cap of FIG. 1.

The evenly-dashed broken lines in the drawings illustrate the portions of the design that form no part of the claim. The dash-dot broken lines in the drawings define the bounds of the claim and form no part thereof.
